[57] CLAIM

The ornamental design for a carriage house playhouse,
as shown.

DESCRIPTION

FIG. 1 is a front perspective view of a carriage house
playhouse, showing my new design;

FIG. 2 is a front elevational view thereof;

FIG. 3 is an end elevational view of the end opposite
that shown in FIG. 1; and

FIG. 4 is a rear elevational view thereof.

FIG.1**FIG.2**

FIG. 3**FIG. 4**
